UNITED STATES PATENT OFFICE.

JOHN N. SCHWALEN, OF NEW RICHMOND, WISCONSIN.

BAG HOLDER.

1,415,901.

Specification of Letters Patent. Patented May 16, 1922.

Application filed July 21, 1921. Serial No. 486,552.

To all whom it may concern:

Be it known that I, JOHN N. SCHWALEN, a citizen of the United States, residing at New Richmond, in the county of St. Croix 5 and State of Wisconsin, have invented certain new and useful Improvements in Bag Holders; and I do declare the following to be a full, clear, and exact description of the invention, such as will enable others skilled 10 in the art to which it appertains to make and use the same.

This invention relates to an improved bag holder and one object of the invention is to provide a bag holder which may be adjusted 15 according to the size of the bag and which may further be adjusted so that when the bag is held open, it may present a mouth which will be either substantially square, oblong or triangular, thus permitting of the 20 bag being held open with the mouth portion of the bag shaped in the most convenient shape according to the scoop or other implement which is being used in filling the sack.

Another object of the invention is to provide 25 a bag holder in which a hanger may be slidably connected with a supporting strip in a very efficient manner, the hanger being permitted to have free sliding movement but prevented from having transverse movement 30 and spring means being provided to limit downward movement of the hanger.

Another object of the invention is to provide improved means for adjustably connecting the supporting strip with a standard 35 so that this supporting strip can be vertically adjusted and securely but releasably held in the adjusted position.

Another object of the invention is to provide 40 a bag holder so constructed that the bag may be easily and quickly connected with the holder and further so constructed that there will be no danger of the bag accidentally slipping out of engagement with the holder.

45 This invention is illustrated in the accompanying drawings, wherein:

Figure 1 is a view showing the improved bag holder in front elevation.

Figure 2 is a view showing the bag holder 50 in vertical section and taken along the line 2-2 of Fig. 1.

Figure 3 is a transverse sectional view taken along the line 3-3 of Fig. 1.

Figure 4 is a transverse sectional view 55 taken along the line 4-4 of Fig. 1.

This improved bag holder is provided

with a standard 1 which is carried by a base 2 and connected with the base by means of brackets 3. This standard is provided adjacent its upper end with an opening to receive the securing bolt 4 and adjacent its lower end is provided with a longitudinally extending recess or pocket 5 from which leads 60 openings 6. A supporting strip 7 is carried by this standard 1 and is provided with outstanding side flanges 8 and with a longitudinally extending slot 9. This supporting strip may be formed from a single length of channel iron or may be formed of two 65 separate strips of angle iron which will be connected at their upper and lower ends by cross strips 10 and 11. The securing bolt 4 passes through the slot 9 and carries a washer 12 and winged nuts 13 which will be tightened to bring the washer plate 12 into 70 tight engagement with the side portions of the supporting strip 7 and hold the strip against longitudinal movement. The cross strip 11 at the lower end of the supporting 75 strip carries a pin 14 which is secured by 80 securing nuts 15 and 16. The securing nut 16 extends into the pocket 5 and the pin 14 is intended to pass through into a selected opening 6 so that the strip may be vertically adjusted and supported in the adjusted 85 position by means of the pin. A bracket 17 is carried by the supporting strip intermediate 90 its height and is provided with arms having inwardly extending end portions 17' for engaging a hanger 18 formed with side 90 flanges 19 and having at its upper end a tongue which is bent to provide a bearing 20 in which will be mounted an anchor 21 which is provided with hook-shaped end 95 portions for engaging the lower ends of springs 22. These springs 22 have their upper ends connected with a yoke 23 which is suspended in openings formed in the side flanges 8 of the strip 7 and it will thus be seen that the hanger 18 will be permitted of 100 free sliding movement but will be yieldably held in a raised position. It will be further noted that the hanger will be held in proper engagement with the supporting strip and will be prevented from having transverse 105 movement.

A cross bar 24 extends transversely of the hanger and is provided with a longitudinally extending slot 25 and with upper and lower strips which form forwardly extending upper and lower flanges 26 and 27. The lower strip 27 has secured thereto a plate 110

28 which extends rearwardly of the cross bar into the supporting strip 7 between the side flanges 8 thereof thus assisting in preventing the hanger from having transverse movement.

Carriers or blocks 29 are slidably carried by the cross bar 24 and are provided with slots 30 through which pass securing bolts 31 carried by the cross bar. When these securing bolts are loosened, the carrier blocks can be adjusted longitudinally of the cross bar and when the securing bolts are again tightened, the carrier blocks will be securely held in the adjusted position. These carrier blocks are provided with upper and lower protector strips 32 which are extended beyond the ends of the blocks to provide hinged ears between which will be pivotally mounted arms 33. These arms 33 extend forwardly and rearwardly of the carrier blocks and at their rear ends are provided with hooks 34 for engagement by springs 35. The springs 35 extend through the slots of the cross bar and are connected with the inner end portions of the carrier blocks as shown in Fig. 4. It will thus be seen that the arms will be normally held to extend forwardly in diverging relation. The outer end portions of these arms 30 are provided with slots 36 through which will pass securing bolts 37 carried by the sack engaging plates 38. These plates 38 are provided with hook-shaped lower end portions 39 for engaging a sack as shown in Fig. 1. Strips 40 are secured to the carrier blocks 29 and extend downwardly beneath the same and are provided with hook-shaped lower end portions for engaging a sack as shown in Fig. 2.

When this device is in use, the supporting strip will be vertically adjusted according to the length of the sack to be filled. The open end portion of the sack will be engaged upon the hooks of the strips 40 and the arms 33 will then be moved toward each other against the tension of the springs 35 and the hooked portions of the plates 38 engaged by the sack. The arms can then be released and the springs will move the arms to the position shown in Figs. 3 and 4. The sack will then be securely engaged by the hooks and will be firmly held in place. By adjusting

the carrier blocks and by adjusting the plates 38, the device can be adjusted to accommodate a narrow or wide sack and further by means of this adjustment, the sack can be caused to be held open in substantially a square, oblong or triangle. The sack can thus be held open in the desired shape and can be very readily filled.

I claim:

1. A sack holder comprising a support, a hanger slidably carried by said support and yieldably held against downward movement, a longitudinally slotted cross bar carried by said hanger and having upper and lower flanges, carrier blocks between the flanges of said cross bar and adjustable longitudinally thereof, arms pivotally connected with the outer end portions of said blocks and extending forwardly and rearwardly thereof, springs connected with said blocks and extending through the slot of the cross bar and connected with the rear ends of said arms, and sack engaging means carried by said blocks and the forward portions of said arms.

2. A sack holder comprising a hanger, a cross bar carried by said hanger and having a slot therein, carrier blocks carried by said cross bar and adjustable longitudinally thereof, arms pivotally connected with the outer end portions of the blocks and extending forwardly and rearwardly thereof, springs connected with the blocks and extending through the slot of the cross bar and connected with said arms, and bag engaging means carried by the blocks and arms.

3. A sack holder comprising a standard, a supporting strip carried by said standard and provided with side flanges, a fastener carried by said standard and passing through a longitudinally extending slot in said strip, and a pin extending from the lower end of said strip for fitting into an opening in the lower portion of said standard.

4. The structure of claim 3 and a carrier slidably longitudinally of the strip between the side flanges thereof, and sack-engaging means associated with said carrier.

In testimony whereof I have hereunto set my hand,

JOHN N. SCHWALEN.
